UNITED STATES PATENT OFFICE.

JOHN WM. FRANZ, OF ST. LOUIS, MISSOURI, ASSIGNOR OF ONE-HALF TO CHARLES F. FRANZ, OF STAUNTON, ILLINOIS.

BABY HIGH CHAIR.

Application filed November 30, 1921. Serial No. 518,861.

To all whom it may concern:

Be it known that I, JOHN W. FRANZ, a citizen of the United States, residing at St. Louis, State of Missouri, have invented certain new and useful Improvements in Baby High Chairs, of which the following is a specification.

My invention has relation to improvements in baby high-chairs, and consists in the novel features of construction more fully set forth in the specification and pointed out in the claims.

The object of the present invention is to provide a high-chair having springs interposed between the body of the chair and the legs so that said body may be gently reciprocated when desired. A further object is to provide a high-chair that may be converted into a crib at a moment's notice by simply readjusting the parts composing the chair body. Further and other advantages will be readily apparent from a detailed description of the invention in connection with the accompanying drawings, in

25 which—

Figure 1 is a side elevation of the chair with the parts shown dotted in their readjusted position to form a crib; Fig. 2 is a top plan of the chair in normal position; Fig. 3 is a front elevation of the chair in normal position; Fig. 4 is a detail view showing the brackets and rod on which the chair back and table swing.

Referring to the drawings, B represents the chair base on which the chair body C is supported from suitable springs S. The construction of the base B forms no part of the present invention, as that forms the subject-matter of United States Patent No. 1,377,332 issued to Louis G. Franz on May 10th, 1921. In fact, so far as the present invention is concerned, the chair may merely be supported by four legs, as is generally the case. Suitably supported by the base B is the chair bottom 1, the four corners of which are notched out at n, n', n', the front notches, n, n receiving hinge members 2, 2 terminating the sides 3, 3 of a foot rest 4, and the rear notches n', n' receiving similar hinge members 5, 5 secured to the sides of the chair back 6 adjacent the lower edge of said back. The foot rest is pivotally mounted on the bottom by hinge pins 7, 7, and the back 6 is also pivotally mounted on the bottom by hinge pins 8, 8, said foot rest

and back being preferably secured in place before the arms 9, 9 are secured to said bottom. The hinge pins 7, 7 and 8, 8 preferably pass through the bottom rail 10, 10 of the arm rests.

Brackets 11, 11 are secured to the seat bottom 1 and project downwardly from each rear corner thereof, the free end of each bracket carrying a tubular head 12 having a reduced threaded portion 12' extending inwardly at the base of which is a shoulder 13. A hollow tube 14 provided with a medial grip 15 and having a nut 16 positioned over each end is positioned between the brackets 11, 11. The nuts 16, 16 are provided with a slotted extension on their inner ends, the slots r, r of each of which receive pins 17, 17 projecting from each end of the tube 14 and as the tube is rotated the nuts will also rotate and be free to slide back and forth on the tube, which movement is necessary since the outer ends of the nuts have right and left hand taps respectively for receiving the threaded portion 12' of each bracket, said brackets also having right and left threads respectively. The back 6 is supported in its normal upright position by a pair of lever arms 18, 18 pivoted at their upper ends to brackets 19, 19 secured to the rear of the back, the lower end of each of said arms 18, 18 being forked at 20, to receive one end of a brace bar 21, the other end of the brace bar being pivotally mounted in a bracket 22 fixed to the back of one side 3 of the foot rest 4. The arms 18, 18 are each provided with a slot m extending from the fork 20 upwardly about one-third the length of the arm, and when the arms 18, 18 are connected they are mounted on the extensions 12' of the brackets 11 (that is, this extension passes through slot m) in abutting relation with shoulders 13. Now, when the tube 14 is positioned between the brackets and the nuts 16 are screwed over extensions 12', 12' said nuts will be brought against the arms 18 and when screwed home, will hold said arms in place.

A table 23 is normally positioned across the front of the arms 9, 9, said table having a web 24 in each upper front corner and one end of each of a pair of lever arms 25, 25 is provided with a boss 26 into which is screwed a stud 27 after the same is passed through the web 24. The other end of each

arm 25 is provided with a slot *p* and a bolt 28 is passed through the tube 14 and the slot *p* of both arms 25, said bolt having a head 29 at one end, and the other end being threaded to receive a wing nut 30. As the wing nut is screwed tight the lever arms 25, 25 will be drawn tightly against the heads 12, 12 of brackets 11, 11 and secured in place.

10 From the above it will be apparent that on turning the tube 14 by means of the grip 15 the arms 18, 18 will be bound tightly or loosened, thus holding the back in place or allowing it to drop down to the position shown dotted (Fig. 1) and by turning the wing nut 30 the table 23 may be secured in its normal position or loosened so that it may also be swung around to the dotted position (Fig. 1). When the back 6 is dropped 15 downwardly in line with the bottom 1 the arms will travel forwardly on the extension 12' of the brackets 11 and swing the foot rest 4 forwardly, which may then be raised to form a further extension of the bottom 1. 20 When the parts are in the positions shown dotted (Fig. 1) they are again locked by tightening the tube 14 and wing nut 30, and a substantial crib is formed. It will be observed that when the chair is converted into 25 a crib the arms 18 form a truss with the bars 21, thus insuring an absolutely rigid structure.

Having described my invention, I claim:

1. In combination with a base, a chair body mounted thereon, said chair body comprising a seat, a back hinged thereto and a foot rest hinged to the seat opposite to the back, a pair of brackets fixed to said seat, a pair of lever arms pivotally connected to said back and having a sliding connection with said brackets, connecting rods between said levers and foot rest, said back and foot rest being adapted for adjustment to form a continuation of the seat thereby converting the chair body into a bed, the lever arms 45 and connecting rods forming a truss when the parts are so adjusted, and means for clamping the lever arms to the brackets. 40

2. In combination with a base, a chair body comprising a seat and a back hinged thereto, a table disposed to the front of and in a plane above the seat, a pair of brackets fixed to said seat, a pair of lever arms pivotally connected to the back and having a sliding connection with the brackets, a rod traversing the brackets, a second pair of lever arms pivotally connected to the aforesaid table and mounted on said rod, means for clamping the first mentioned lever arms to the brackets, and independent 55 means for clamping the last mentioned lever arms to the brackets. 50

In testimony whereof I hereunto affix my signature:

JOHN WM. FRANZ.
